UNITED STATES PATENT OFFICE

LEO W. NACK, OF CHICAGO, ILLINOIS

COLLAPSIBLE STEEL CABLE REEL

Application filed June 5, 1930. Serial No. 459,299.

This invention relates, generally speaking, to reels or drums and particularly to reels for storing and for shipping cables, and is especially concerned with an assembled collapsible metal reel in which numerous novel and advantageous structural and functional features are incorporated.

A drum or reel structure designed in the past for the purpose of storing and of shipping cables usually comprises a central barrel body made of wood and provided with two lateral flanges of the same material. The several parts of such a reel of well known construction are permanently assembled and secured by means of suitable bolts, screws or nails, and the lateral flanges are joined by means of axially extending special bolts. The cable is disposed on the central barrel portion within the storage space defined by the lateral flanges, as on a spool, and the reel is then prepared for shipment by attaching to the flanges so called lagging bars, i. e., wooden cross bars, which are peripherally attached to the flanges and cover the cable coiled on the central barrel body between the flanges. These lagging bars are nailed peripherally to the flanges and finally secured by means of a steel tape which is suitably attached circumferentially around the lagging bars and seals the reel.

I have observed in practice that this method of storing and of shipping cables has numerous disadvantages resulting from the construction of the reel as outlined above, and I will briefly list these disadvantages and objectionable features in the following, so that the description of my invention, which is to follow, may be readily understood and appreciated.

The wooden drum, constructed in the past as intimated above, is merely a temporary article due to the deterioration which is caused as a consequence of its structure. It is apparent that such reel should be so constructed as to represent a permanent article. However, at the present time, such wooden reel can be used with safety only a very limited number of times, say, for about three to four shipments. The flanges become ragged and do not take the nails due to repeated nail-

ing and removal of the lagging bars. In storage, such reels begin to deteriorate, the rotting beginning within the flanges, although the exterior may not display the deterioration. Such reels collapse frequently before the cable stored on them is used.

Therefore, such wooden reels need maintenance and often replacement of parts. One of the parts which is frequently damaged is, for example, the bolts holding the two flanges axially with relation to the central barrel portion. Stresses imposed on the reel often cause bending and even breakage of such a bolt, necessitating replacement which is relatively expensive since these bolts are special equipment. It is very difficult to remove such a bolt from the reel when it is bent out of shape and the use of a torch for cutting the bolt prior to removal is frequently required.

Nails in the wood structure, particularly the nails holding the lagging bars often work loose and damage the cable on the reel. They also represent a hazard to the workmen handling the reel.

The time necessary for attaching the lagging bars to a reel, or for removing the same from a reel, is appreciable due to the fact that the lagging bars are rigidly attached to the flanges by means of nails. Frequently the lagging bars split and break, resulting in wastage. In addition, there is the ever present danger of injury to the workmen engaged in handling the reels and the possibility of damage to the cable.

The old wooden reel structure does not lend itself to standardization of parts applicable to different sizes of reels. Accordingly there are at the present time numerous different structures used, designed to meet the requirements of reels of the various sizes and for different purposes.

The weight of a large wooden reel is considerable due to the massive structure required for supporting the great weight of a cable and due to the fact that the reel must withstand the wear of transportation and installation. The rolling of the reel over uneven ground imposes great stresses upon the reel structure, damaging its parts.

Empty reels when returned to the factory

consume a large amount of car space. In case of a 72 inch reel, a size widely used at the present time, only twelve such reels can be transported in an ordinary 36 foot car.

5 The principal aim and purpose of my invention, which I am about to describe, is to furnish a novel cable reel which avoids the above and other objectionable features.

Generally speaking, the novel and improved cable reel incorporating the various features of my invention consists in one embodiment of a sectional collapsible central barrel portion which is provided with detachable laterally disposed flanges to form a drum or reel of spool like shape for receiving the cable. Each of the flanges is constructed of a number of interchangeable reinforced sections joined by means of bolts or rivets. A closure cooperating with the corresponding flange and with the barrel portion is removably attached at each end of the barrel portion. An opening thru the end closures provides for rotatably mounting the reel on a suitable shaft. All parts of this reel are made of metal and are standardized throughout, providing for economy of construction and production, and adapting principles of the invention to be applied to various types and sizes of reels for different purposes. The peripheral rim of each of the flanges attached to the barrel portion is provided with peripheral openings for receiving and for holding the lagging bars which are applied to the flanges by simply successively slipping them in place instead of nailing them individually to the rim of the flanges as was done in case of wooden reels. In one embodiment, the lagging bars are slipped in place on the flanges endwise and are held collectively against axial displacement by means of a suitable locking provision.

Some of the advantages resulting from my invention are enumerated below as follows:

The steel reel of my novel structure is a permanent article, requiring for maintenance merely an occasional spray with paint. Deterioration is practically negligible as compared with the deterioration occurring in wooden reels. Replacements of parts, should such replacements become necessary, are easily carried out and are inexpensive since all parts are standardized.

The use of nails is eliminated, avoiding the danger of injury to the workmen and damage to the cable.

The time for attaching lagging bars to the steel reel and for removing the same is reduced to about one-third as compared with the time required for attaching the lagging bars used in connection with prior construction of wooden reels.

The weight of the reel is reduced, and, at the same time, its production cost is decreased without in any way impairing the reliability of its operation. In fact, the re-

liability of the collapsible steel reel made in accordance with my invention is greater than that of prior structures.

The reel can be readily taken apart when empty, and prepared for shipment to the factory, the individual parts consuming only about one-third of the car space now required for shipping wooden reels. This means in practice that the parts for about thirty-six reels of my novel structure can be shipped in a 36 foot railroad car instead of only twelve reels as formerly, thus reducing the shipping expenses appreciably.

Breakage and wastage is largely eliminated; the structure is solid, reliable and easily assembled and taken apart. It requires no maintenance except the application of an occasional coat of paint, and by its use, the danger from nails is entirely avoided.

The various objects attained by my invention are listed separately below:

One object of the invention relates to the provision of an axially split tubular central barrel body of metal cooperating with a plurality of assembled sectional metal flange members to form a spool shaped collapsible reel for storing and for shipping cables.

Another object relates to assembling each of the flanges of a plurality of interchangeable sections to form a reinforced ring-shaped structure.

A further object has to do with the provision of mounting the metal flanges on the tubular metal barrel body solely by means of radially extending bolts.

Still another object is concerned with the provision of a brace and spacing member located centrally within the tubular central body for circularly bracing the structure of the barrel and for simplifying its assembly.

Another object has to do with the provision of end closures for removable central attachment to the barrel body at each end.

A further object resides in the provision of axially disposed peripheral rim extensions integral with the sectional flange members, and the provision of peripheral openings in said rim extensions for receiving and for holding suitable lagging bars across the flanges for covering the cable disposed on the central barrel body between the flanges.

Still another object has to do with disposing the openings in certain of the flange sections, in one embodiment, in such a manner as to cooperate with the openings in the other flange sections to prevent peripheral circular displacement of the lagging bars held by said openings.

Another object is concerned with the provision of special openings in some of said flange sections for receiving blank lagging bars.

Still another object, in connection with a certain embodiment of the invention, has to

do with provisions for locking the lagging bars collectively on the reel flanges.

Another object, in connection with a certain embodiment of the invention, is concerned with sectional movable collective locking provisions for the lagging bars.

A further object relates to the provision of a cross bar assembly holding a bearing bracket and attachable at each end of the 10 tubular barrel body in radial cooperation with the lateral metal flange sections and centrally in the end closures.

Another object is concerned with the provision of lagging bars, each provided with 15 key members for engaging the openings in the flanges to cover the cable disposed within the flanges on the tubular barrel body.

Other objects not specifically noted above will appear from the following detailed 20 description furnished with reference to the accompanying drawings in which:

Figure 1 represents a perspective view of one embodiment of the invention showing an assembled reel with some of the lagging bars 25 attached and with certain parts broken away in order to illustrate details;

Figure 2 illustrates the collapsible barrel body, with parts broken away in order to show the bracing and spacing disk located 30 within the barrel when assembled;

Figure 3 shows an end closure for attachment to the barrel body;

Figure 4 is a transversal cross section of the end closure shown in Figure 3;

Figure 5 shows a single section of the lateral flange attached to the barrel member;

Figure 6 is a reinforcing part cooperating with the section of the flange shown in Figure 5;

Figure 7 shows the bearing plate, used in connection with one modification of the reel;

Figure 8 illustrates a cross section of the completely assembled reel;

Figure 9 represents an end view of the assembled reel;

Figure 10 shows the key used in connection with the lagging bars;

Figure 11 is a side view and a cross section, respectively, of a lagging bar used with one 50 embodiment of the invention;

Figure 12 shows a fragmentary side view and a cross section, respectively, of a blank lagging bar;

Figure 13 illustrates the manner in which 55 the lagging bars may be bundled for shipment or storage;

Figure 14 shows the manner in which the collapsed barrel may be arranged for shipment;

Figure 15 represents a fragmentary perspective view of a reel showing differently disposed openings for attaching the lagging bars endwise and for locking them collectively on the reel by means of a suitable ring 60 attached to one of the flanges;

Figure 16 illustrates a modified form of lagging bar in side view and an end view, respectively;

Figure 17 shows a modification of a sectional collective locking ring for locking the 70 lagging bars endwise;

Figure 18 is a further modification showing how the locking ring may be secured against radial displacement on the flange;

Figures 19 and 20 illustrate still another 75 modification of a sectional collective locking ring for the lagging bars, Figure 19 showing the sections of the locking ring in disengaged position, and Figure 20 in engaged position;

Figure 21 is a modification of the cover 80 laggings, being made of sections of curved metal bodies provided with keys for engaging the openings on the flanges; and

Figure 22 illustrates a side view of the metal cover shown in Figure 21. 85

Referring now to Figure 1, this figure represents one embodiment of the assembled reel with some of the lagging bars attached thereto. It will be understood, of course, that the lagging bars have been shown in this figure attached to the flanges of the reel merely for illustrative purposes. In practice, these lagging bars will be attached only when the cable is disposed on the barrel between the flanges, in order to complete the reel 90 for shipment.

The reel comprises the collapsible barrel body designated by numeral 1. The detailed structure of this barrel body will be described presently. At each end of this tubular barrel body is attached a recessed end closure, each having a laterally extending flange such as shown at 5 in connection with the end closure 4. Each of the laterally extending flanges or heads 2 and 3 is constructed of eight sections. These sections are designated by reference numerals 12 to 19, inclusive, in connection with the flange 3, the flange 2 being largely concealed in this figure and showing only the sections 20 to 23, inclusive. Each of these flange sections comprises a suitable tray structure having a reinforcing insert comprising a channel shaped rim section, such as the one designated by numeral 25 shown in connection with the flange section 19 of flange 100 3, side members 35 and 36, and bracket members 37 and 38. The flange section designated by the numeral 12 comprises again the external tray section mentioned before and the reinforcing insert having a channel member 105 24, side arms 39 and 40, and the brackets 41 and 42. Each of the flanges has eight similarly constructed sections, the inserts of the various flange sections being marked by reference numerals 24 to 31, inclusive. The eight 110 sections of the flange are bolted or riveted together to form a sectional ring shaped structure. The bolts or rivets holding the sections 12 and 19 being designated by reference numerals 47, 48 and 49; the bolts holding 115

the sections 20 to 23 being designated by reference numerals 44, 45 and 46; the bolts holding the sections 24 to 31 being designated by reference numerals 40, 41 and 42; the bolts holding the sections 35 and 36 being designated by reference numerals 43, 44 and 45; the bolts holding the sections 37 and 38 being designated by reference numerals 46, 47 and 48; the bolts holding the sections 39 and 40 being designated by reference numerals 49, 50 and 51; the bolts holding the sections 41 and 42 being designated by reference numerals 52, 53 and 54; the bolts holding the sections 47, 48 and 49 being designated by reference numerals 55, 56 and 57; the bolts holding the sections 44, 45 and 46 being designated by reference numerals 58, 59 and 60; the bolts holding the sections 43, 44 and 45 being designated by reference numerals 61, 62 and 63; the bolts holding the sections 46, 47 and 48 being designated by reference numerals 64, 65 and 66; the bolts holding the sections 49, 50 and 51 being designated by reference numerals 67, 68 and 69; the bolts holding the sections 52, 53 and 54 being designated by reference numerals 70, 71 and 72; the bolts holding the sections 55, 56 and 57 being designated by reference numerals 73, 74 and 75; the bolts holding the sections 58, 59 and 60 being designated by reference numerals 76, 77 and 78; the bolts holding the sections 61, 62 and 63 being designated by reference numerals 79, 80 and 81; the bolts holding the sections 64, 65 and 66 being designated by reference numerals 82, 83 and 84; the bolts holding the sections 67, 68 and 69 being designated by reference numerals 85, 86 and 87; the bolts holding the sections 70, 71 and 72 being designated by reference numerals 88, 89 and 90; the bolts holding the sections 73, 74 and 75 being designated by reference numerals 91, 92 and 93; the bolts holding the sections 76, 77 and 78 being designated by reference numerals 94, 95 and 96; the bolts holding the sections 79, 80 and 81 being designated by reference numerals 97, 98 and 99; the bolts holding the sections 82, 83 and 84 being designated by reference numerals 100, 101 and 102; the bolts holding the sections 85, 86 and 87 being designated by reference numerals 103, 104 and 105; the bolts holding the sections 88, 89 and 90 being designated by reference numerals 106, 107 and 108; the bolts holding the sections 91, 92 and 93 being designated by reference numerals 109, 110 and 111; the bolts holding the sections 94, 95 and 96 being designated by reference numerals 112, 113 and 114; the bolts holding the sections 97, 98 and 99 being designated by reference numerals 115, 116 and 117; the bolts holding the sections 100, 101 and 102 being designated by reference numerals 118, 119 and 120; the bolts holding the sections 103, 104 and 105 being designated by reference numerals 121, 122 and 123; the bolts holding the sections 106, 107 and 108 being designated by reference numerals 124, 125 and 126; the bolts holding the sections 109, 110 and 111 being designated by reference numerals 127, 128 and 129; the bolts holding the sections 112, 113 and 114 being designated by reference numerals 130, 131 and 132; the bolts holding the sections 115, 116 and 117 being designated by reference numerals 133, 134 and 135; the bolts holding the sections 118, 119 and 120 being designated by reference numerals 136, 137 and 138; the bolts holding the sections 121, 122 and 123 being designated by reference numerals 139, 140 and 141; the bolts holding the sections 124, 125 and 126 being designated by reference numerals 142, 143 and 144; the bolts holding the sections 127, 128 and 129 being designated by reference numerals 145, 146 and 147; the bolts holding the sections 124, 125 and 126 being designated by reference numerals 148, 149 and 150; the bolts holding the sections 133, 134 and 135 being designated by reference numerals 151, 152 and 153; the bolts holding the sections 136, 137 and 138 being designated by reference numerals 154, 155 and 156; the bolts holding the sections 139, 140 and 141 being designated by reference numerals 157, 158 and 159; the bolts holding the sections 142, 143 and 144 being designated by reference numerals 160, 161 and 162; the bolts holding the sections 145, 146 and 147 being designated by reference numerals 163, 164 and 165; the bolts holding the sections 148, 149 and 150 being designated by reference numerals 166, 167 and 168; the bolts holding the sections 151, 152 and 153 being designated by reference numerals 169, 170 and 171; the bolts holding the sections 154, 155 and 156 being designated by reference numerals 172, 173 and 174; the bolts holding the sections 157, 158 and 159 being designated by reference numerals 175, 176 and 177; the bolts holding the sections 160, 161 and 162 being designated by reference numerals 178, 179 and 180; the bolts holding the sections 163, 164 and 165 being designated by reference numerals 181, 182 and 183; the bolts holding the sections 166, 167 and 168 being designated by reference numerals 184, 185 and 186; the bolts holding the sections 169, 170 and 171 being designated by reference numerals 187, 188 and 189; the bolts holding the sections 172, 173 and 174 being designated by reference numerals 190, 191 and 192; the bolts holding the sections 175, 176 and 177 being designated by reference numerals 193, 194 and 195; the bolts holding the sections 178, 179 and 180 being designated by reference numerals 196, 197 and 198; the bolts holding the sections 181, 182 and 183 being designated by reference numerals 199, 200 and 201; the bolts holding the sections 184, 185 and 186 being designated by reference numerals 202, 203 and 204; the bolts holding the sections 187, 188 and 189 being designated by reference numerals 205, 206 and 207; the bolts holding the sections 190, 191 and 192 being designated by reference numerals 208, 209 and 210; the bolts holding the sections 193, 194 and 195 being designated by reference numerals 211, 212 and 213; the bolts holding the sections 196, 197 and 198 being designated by reference numerals 214, 215 and 216; the bolts holding the sections 199, 200 and 201 being designated by reference numerals 217, 218 and 219; the bolts holding the sections 202, 203 and 204 being designated by reference numerals 220, 221 and 222; the bolts holding the sections 205, 206 and 207 being designated by reference numerals 223, 224 and 225; the bolts holding the sections 208, 209 and 210 being designated by reference numerals 226, 227 and 228; the bolts holding the sections 211, 212 and 213 being designated by reference numerals 229, 230 and 231; the bolts holding the sections 214, 215 and 216 being designated by reference numerals 232, 233 and 234; the bolts holding the sections 217, 218 and 219 being designated by reference numerals 235, 236 and 237; the bolts holding the sections 220, 221 and 222 being designated by reference numerals 238, 239 and 240; the bolts holding the sections 223, 224 and 225 being designated by reference numerals 241, 242 and 243; the bolts holding the sections 226, 227 and 228 being designated by reference numerals 244, 245 and 246; the bolts holding the sections 229, 230 and 231 being designated by reference numerals 247, 248 and 249; the bolts holding the sections 232, 233 and 234 being designated by reference numerals 250, 251 and 252; the bolts holding the sections 235, 236 and 237 being designated by reference numerals 253, 254 and 255; the bolts holding the sections 238, 239 and 240 being designated by reference numerals 256, 257 and 258; the bolts holding the sections 241, 242 and 243 being designated by reference numerals 259, 260 and 261; the bolts holding the sections 244, 245 and 246 being designated by reference numerals 262, 263 and 264; the bolts holding the sections 247, 248 and 249 being designated by reference numerals 266, 267 and 268; the bolts holding the sections 250, 251 and 252 being designated by reference numerals 271, 272 and 273; the bolts holding the sections 253, 254 and 255 being designated by reference numerals 276, 277 and 278; the bolts holding the sections 256, 257 and 258 being designated by reference numerals 281, 282 and 283; the bolts holding the sections 259, 260 and 261 being designated by reference numerals 284, 285 and 286; the bolts holding the sections 262, 263 and 264 being designated by reference numerals 289, 290 and 291; the bolts holding the sections 266, 267 and 268 being designated by reference numerals 294, 295 and 296; the bolts holding the sections 271, 272 and 273 being designated by reference numerals 299, 300 and 301; the bolts holding the sections 276, 277 and 278 being designated by reference numerals 304, 305 and 306; the bolts holding the sections 281, 282 and 283 being designated by reference numerals 308, 309 and 310; the bolts holding the sections 284, 285 and 286 being designated by reference numerals 313, 314 and 315; the bolts holding the sections 289, 290 and 291 being designated by reference numerals 318, 319 and 320; the bolts holding the sections 294, 295 and 296 being designated by reference numerals 323, 324 and 325; the bolts holding the sections 299, 300 and 301 being designated by reference numerals 328, 329 and 330; the bolts holding the sections 304, 305 and 306 being designated by reference numerals 333, 334 and 335; the bolts holding the sections 308, 309 and 310 being designated by reference numerals 338, 339 and 340; the bolts holding the sections 313, 314 and 315 being designated by reference numerals 343, 344 and 345; the bolts holding the sections 318, 319 and 320 being designated by reference numerals 348, 349 and 350; the bolts holding the sections 323, 324 and 325 being designated by reference numerals 353, 354 and 355; the bolts holding the sections 328, 329 and 330 being designated by reference numerals 358, 359 and 360; the bolts holding the sections 333, 334 and 335 being designated by reference numerals 363, 364 and 365; the bolts holding the sections 338, 339 and 340 being designated by reference numerals 368, 369 and 370; the bolts holding the sections 343, 344 and 345 being designated by reference numerals 373, 374 and 375; the bolts holding the sections 348, 349 and 350 being designated by reference numerals 378, 379 and 380; the bolts holding the sections 353, 354 and 355 being designated by reference numerals 383, 384 and 385; the bolts holding the sections 358, 359 and 360 being designated by reference numerals 388, 389 and 390; the bolts holding the sections 363, 364 and 365 being designated by reference numerals 393, 394 and 395; the bolts holding the sections 368, 369 and 370 being designated by reference numerals 398, 399 and 400; the bolts holding the sections 373, 374 and 375 being designated by reference numerals 403, 404 and 405; the bolts holding the sections 378, 379 and 380 being designated by reference numerals 408, 409 and 410; the bolts holding the sections 383, 384 and 385 being designated by reference numerals 413, 414 and 415; the bolts holding the sections 388, 389 and 390 being designated by reference numerals 418, 419 and 420; the bolts holding the sections 393, 394 and 395 being designated by reference numerals 423, 424 and 425; the bolts holding the sections 398, 399 and 400 being designated by reference numerals 428, 429 and 430; the bolts holding the sections 403, 404 and 405 being designated by reference numerals 433, 434 and 435; the bolts holding the sections 408, 409 and 410 being designated by reference numerals 438, 439 and 440; the bolts holding the sections 413, 414 and 415 being designated by reference numerals 443, 444 and 445; the bolts holding the sections 418, 419 and 420 being designated by reference numerals 448, 449 and 450; the bolts holding the sections 423, 424 and 425 being designated by reference numerals 453, 454 and 455; the bolts holding the sections 428, 429 and 430 being designated by reference numerals 458, 459 and 460; the bolts holding the sections 433, 434 and 435 being designated by reference numerals 463, 464 and 465; the bolts holding the sections 438, 439 and 440 being designated by reference numerals 468, 469 and 470; the bolts holding the sections 443, 444 and 445 being designated by reference numerals 473, 474 and 475; the bolts holding the sections 448, 449 and 450 being designated by reference numerals 478, 479 and 480; the bolts holding the sections 453, 454 and 455 being designated by reference numerals 483, 484 and 485; the bolts holding the sections 458, 459 and 460 being designated by reference numerals 488, 489 and 490; the bolts holding the sections 463, 464 and 465 being designated by reference numerals 493, 494 and 495; the bolts holding the sections 468, 469 and 470 being designated by reference numerals 498, 499 and 500; the bolts holding the sections 473, 474 and 475 being designated by reference numerals 503, 504 and 505; the bolts holding the sections 478, 479 and 480 being designated by reference numerals 508, 509 and 5010; the bolts holding the sections 483, 484 and 485 being designated by reference numerals 513, 514 and 515; the bolts holding the sections 488, 489 and 490 being designated by reference numerals 518, 519 and 510; the bolts holding the sections 493, 494 and 495 being designated by reference numerals 523, 524 and 525; the bolts holding the sections 498, 499 and 500 being designated by reference numerals 528, 529 and 520; the bolts holding the sections 503, 504 and 505 being designated by reference numerals 533, 534 and 535; the bolts holding the sections 508, 509 and 5010 being designated by reference numerals 538, 539 and 530; the bolts holding the sections 513, 514 and 515 being designated by reference numerals 543, 544 and 545; the bolts holding the sections 518, 519 and 510 being designated by reference numerals 548, 549 and 540; the bolts holding the sections 523, 524 and 525 being designated by reference numerals 553, 554 and 555; the bolts holding the sections 528, 529 and 520 being designated by reference numerals 558, 559 and 550; the bolts holding the sections 533, 534 and 535 being designated by reference numerals 563, 564 and 565; the bolts holding the sections 538, 539 and 530 being designated by reference numerals 568, 569 and 560; the bolts holding the sections 543, 544 and 545 being designated by reference numerals 573, 574 and 575; the bolts holding the sections 548, 549 and 540 being designated by reference numerals 578, 579 and 570; the bolts holding the sections 553, 554 and 555 being designated by reference numerals 578, 579 and 570; the bolts holding the sections 558, 559 and 550 being designated by reference numerals 583, 584 and 585; the bolts holding the sections 563, 564 and 565 being designated by reference numerals 568, 569 and 560; the bolts holding the sections 568, 569 and 560 being designated by reference numerals 568, 569 and 560; the bolts holding the sections 573, 574 and 575 being designated by reference numerals 578, 579 and 570; the bolts holding the sections 578, 579 and 570 being designated by reference numerals 578, 579 and 570; the bolts holding the sections 583, 584 and 585 being designated by reference numerals 588, 589 and 580; the bolts holding the sections 588, 589 and 580 being designated by reference numerals 588, 589 and 580; the bolts holding the sections 593, 594 and 595 being designated by reference numerals 598, 599 and 590; the bolts holding the sections 598, 599 and 590 being designated by reference numerals 598, 599 and 590; the bolts holding the sections 603, 604 and 605 being designated by reference numerals 608, 609 and 600; the bolts holding the sections 608, 609 and 600 being designated by reference numerals 608, 609 and 600; the bolts holding the sections 613, 614 and 615 being designated by reference numerals 618, 619 and 610; the bolts holding the sections 618, 619 and 610 being designated by reference numerals 618, 619 and 610; the bolts holding the sections 623, 624 and 625 being designated by reference numerals 628, 629 and 620; the bolts holding the sections 628, 629 and 620 being designated by reference numerals 628, 629 and 620; the bolts holding the sections 633, 634 and 635 being designated by reference numerals 638, 639 and 630; the bolts holding the sections 638, 639 and 630 being designated by reference numerals 638, 639 and 630; the bolts holding the sections 643, 644 and 645 being designated by reference numerals 648, 649 and 640; the bolts holding the sections 648, 649 and 640 being designated by reference numerals 648, 649 and 640; the bolts holding the sections 653, 654 and 655 being designated by reference numerals 658, 659 and 650; the bolts holding the sections 658, 659 and 650 being designated by reference numerals 658, 659 and 650; the bolts holding the sections 663, 664 and 665 being designated by reference numerals 668, 669 and 660; the bolts holding the sections 668, 669 and 660 being designated by reference numerals 668, 669 and 660; the bolts holding the sections 673, 674 and 675 being designated by reference numerals 678, 679 and 670; the bolts holding the sections 678, 679 and 670 being designated by reference numerals 678, 679 and 670; the bolts holding the sections 683, 684 and 685 being designated by reference numerals 688, 689 and 680; the bolts holding the sections 688, 689 and 680 being designated by reference numerals 688, 689 and 680; the bolts holding the sections 693, 694 and 695 being designated by reference numerals 698, 699 and 690; the bolts holding the sections 698, 699 and 690 being designated by reference numerals 698, 699 and 690; the bolts holding the sections 703, 704 and 705 being designated by reference numerals 708, 709 and 700; the bolts holding the sections 708, 709 and 700 being designated by reference numerals 708, 709 and 700; the bolts holding the sections 713, 714 and 715 being designated by reference numerals 718, 719 and 710; the bolts holding the sections 718, 719 and 710 being designated by reference numerals 718, 719 and 710; the bolts holding the sections 723, 724 and 725 being designated by reference numerals 728, 729 and 720; the bolts holding the sections 728, 729 and 720 being designated by reference numerals 728, 729 and 720; the bolts holding the sections 733, 734 and 735 being designated by reference numerals 738, 739 and 730; the bolts holding the sections 738, 739 and 730 being designated by reference numerals 738, 739 and 730; the bolts holding the sections 743, 744 and 745 being designated by reference numerals 748, 749 and 740; the bolts holding the sections 748, 749 and 740 being designated by reference numerals 748, 749 and 740; the bolts holding the sections 753, 754 and 755 being designated by reference numerals 758, 759 and 750; the bolts holding the sections 758, 759 and 750 being designated by reference numerals 758, 759 and 750; the bolts holding the sections 763, 764 and 765 being designated by reference numerals 768, 769 and 760; the bolts holding the sections 768, 769 and 760 being designated by reference numerals 768, 769 and 760; the bolts holding the sections 773, 774 and 775 being designated by reference numerals 778, 779 and 770; the bolts holding the sections 778, 779 and 770 being designated by reference numerals 778, 779 and 770; the bolts holding the sections 783, 784 and 785 being designated by reference numerals 788, 789 and 780; the bolts holding the sections 788, 789 and 780 being designated by reference numerals 788, 789 and 780; the bolts holding the sections 793, 794 and 795 being designated by reference numerals 798, 799 and 790; the bolts holding the sections 798, 799 and 790 being designated by reference numerals 798, 799 and 790; the bolts holding the sections 803, 804 and 805 being designated by reference numerals 808, 809 and 800; the bolts holding the sections 808, 809 and 800 being designated by reference numerals 808, 809 and 800; the bolts holding the sections 813, 814 and 815 being designated by reference numerals 818, 819 and 810; the bolts holding the sections 818, 819 and 810 being designated by reference numerals 818, 819 and 810; the bolts holding the sections 823, 824 and 825 being designated by reference numerals 828, 829 and 820; the bolts holding the sections 828, 829 and 820 being designated by reference numerals 828, 829 and 820; the bolts holding the sections 833, 834 and 835 being designated by reference numerals 838, 839 and 830; the bolts holding the sections 838, 839 and 830 being designated by reference numerals 838, 839 and 830; the bolts holding the sections 843, 844 and 845 being designated by reference numerals 848, 849 and 840; the bolts holding the sections 848, 849 and 840 being designated by reference numerals 848, 849 and 840; the bolts holding the sections 853, 854 and 855 being designated by reference numerals 858, 859 and 850; the bolts holding the sections 858, 859 and 850 being designated by reference numerals 858, 859 and 850; the bolts holding the sections 863, 864 and 865 being designated by reference numerals 868, 869 and 860; the bolts holding the sections 868, 869 and 860 being designated by reference numerals 868, 869 and 860; the bolts holding the sections 873, 874 and 875 being designated by reference numerals 878, 879 and 870; the bolts holding the sections 878, 879 and 870 being designated by reference numerals 878, 879 and 870; the bolts holding the sections 883, 884 and 885 being designated by reference numerals 888, 889 and 880; the bolts holding the sections 888, 889 and 880 being designated by reference numerals 888, 889 and 880; the bolts holding the sections 893, 894 and 895 being designated by reference numerals 898, 899 and 890; the bolts holding the sections 898, 899 and 890 being designated by reference numerals 898, 899 and 890; the bolts holding the sections 903, 904 and 905 being designated by reference numerals 908, 909 and 900; the bolts holding the sections 908, 909 and 900 being designated by reference numerals 908, 909 and 900; the bolts holding the sections 913, 914 and 915 being designated by reference numerals 918, 919 and 910; the bolts holding the sections 918, 919 and 910 being designated by reference numerals 918, 919 and 910; the bolts holding the sections 923, 924 and 925 being designated by reference numerals 928, 929 and 920; the bolts holding the sections 928, 929 and 920 being designated by reference numerals 928, 929 and 920; the bolts holding the sections 933, 934 and 935 being designated by reference numerals 938, 939 and 930; the bolts holding the sections 938, 939 and 930 being designated by reference numerals 938, 939 and 930; the bolts holding the sections 943, 944 and 945 being designated by reference numerals 948, 949 and 940; the bolts holding the sections 948, 949 and 940 being designated by reference numerals 948, 949 and 940; the bolts holding the sections 953, 954 and 955 being designated by reference numerals 958, 959 and 950; the bolts holding the sections 958, 959 and 950 being designated by reference numerals 958, 959 and 950; the bolts holding the sections 963, 964 and 965 being designated by reference numerals 968, 969 and 960; the bolts holding the sections 968, 969 and 960 being designated by reference numerals 968, 969 and 960; the bolts holding the sections 973, 974 and 975 being designated by reference numerals 978, 979 and 970; the bolts holding the sections 978, 979 and 970 being designated by reference numerals 978, 979 and 970; the bolts holding the sections 983, 984 and 985 being designated by reference numerals 988, 989 and 980; the bolts holding the sections 988, 989 and 980 being designated by reference numerals 988, 989 and 980; the bolts holding the sections 993, 994 and 995 being designated by reference numerals 998, 999 and 990; the bolts holding the sections 998, 999 and 990 being designated by reference numerals 998, 999 and 990; the bolts holding the sections 1003, 1004 and 1005 being designated by reference numerals 1008, 1009 and 1000; the bolts holding the sections 1008, 1009 and 1000 being designated by reference numerals 1008, 1009 and 1000; the bolts holding the sections 1013, 1014 and 1015 being designated by reference numerals 1018, 1019 and 1010; the bolts holding the sections 1018, 1019 and 1010 being designated by reference numerals 1018, 1019 and 1010; the bolts holding the sections 102

the sections 19 and 18 being designated by reference numerals 50, 51 and 52, while two bolts 53 and 54 are shown in Figure 1 as fastening together the sections 18 and 17.

- 5 When this sectional ring shaped flange structure is assembled as intimated above, it is attached exteriorly to the end of the tubular barrel member 1. There are radially extending openings in the bracket extensions 10 37—38, 41—42, 45—46, etc., and corresponding openings in the flange section holding the reinforcing inserts of which these bracket extensions form a part, and these openings are lined up with corresponding openings in the 15 tubular barrel members when the sectional flange is attached thereto. An end closure such as the closure 4 having a laterally extending rim 5 is then inserted into the tubular barrel member 1. The closure is provided 20 with radially extending openings corresponding to the openings in the barrel member and in the various flange sections as mentioned. The openings are lined up radially and the structure is then completed by inserting 25 radially extending bolts at each end of the barrel member 1, and by fastening these bolts in place by means of nuts such as 55 to 60, inclusive.
- 30 Laterally extending, channel shaped reinforcing bars such as the bars 7 and 8 may be attached within the recessed portion of the end closure, as is shown in connection with the closure 4. These bars extend transversely throughout the recessed portion of the end 35 closure and may be fastened by means of nuts and bolts 61—62 and 63—64. A bearing plate such as shown at 9, having a central opening 10 may be attached to the reinforcing bars 7 and 8 by means of nuts and 40 bolts as indicated by reference numerals 65 to 68 inclusive. Corresponding reinforcing bars may be attached on the other side of the end closure, in the interior of the barrel 1, displaced radially of the bars 7 and 8 by 45 ninety degrees. It will be understood, of course, that the end closure attached to the other end of the barrel is also provided with a centrally located opening in register with the opening 10 of the bearing plate 9 for receiving a shaft to support the reel rotatably 50 when it is desired. It will also be understood that reinforcing bars as discussed in connection with the right hand side of the reel are also provided on the left hand side and disposed within the recessed end closure in the 55 same manner.

- The axially extending exterior rim of each of the flanges 2 and 3 is provided with suitable key openings, such as 69—70 and 71—72. 60 The purpose of these key openings is to receive headed locking keys or studs attached to the lagging bars 11, as will be described in detail later. It may be mentioned at this point, however, that the headed keys or studs 65 in the lagging bars 11 are slipped into the

horizontally extending portion of the T-shaped openings on the rim of the flanges and then moved circularly along the flanges to lock behind the vertically extending portion of the T-shaped openings. It will be 70 observed that the direction of the T-shaped openings provided on the flange sections 20 and 12 is reversed relative to the openings provided on the flange sections 21 and 19. The purpose of this reversal of certain sections is to provide a locking feature for the 75 laggings. When the lagging bars are attached to the flange sections 20—12 and 21—19, respectively, and slipped in place, a space will result for the attachment of a 80 blank lagging bar provided with simple studs for engagement with the openings designated by numerals 6 and 6'. This blank lagging bar is therefore merely a spacer strip and can be readily removed since it is not locked to the flanges. There may be several such blank laggings provided on the reel, each marked by a certain color to denote the places where removal of the lagging bars may be started. These blanks are connected and held in place 85 by means of circularly attached steel tapes nailed to the blanks and holding the same in place on the flanges, thereby sealing the reel for shipment. Since stresses imposed on the other lagging bars cannot dislodge the bars 90 due to the locking arrangement of these bars, and since the blanks are securely held by the steel tapes, it is apparent that removal of the lagging bars is only possible by first removing the blanks and then sliding the other 95 bars out of engagement with the flanges. 100

When it is desired to collapse the reel for shipment, the lagging bars are removed from the flanges as described above, and the radially extending bolts such as 55 to 64, inclusive, are then removed. The flange 3 is then slipped axially from the tubular barrel 1. Since the flange 5 of the end closure 4 extends laterally beyond and overlaps the inner circle of the sectional ring shaped flange 3, the closure 4 will be removed with the flange 3. The other flange 2 is removed from the tubular barrel in the same manner and the barrel will then collapse. 110

The lagging bars are suitably bundled in a manner which will be described presently, and the individual parts of the reel, that is to say, the ring shaped sectional flanges, the end closures and the collapsed barrel will be shipped by arranging them suitably in a car in a manner consuming less space than the usual structures of reels which are not collapsible. The reassembling is equally simple. 115

As shown in Figure 2, the barrel comprises sections 73 and 74. Brackets, such as 75 and 78, inclusive, are attached permanently in each of these sections. A disk 79 having a centrally located opening 146 is provided for simplifying the assembly of the barrel and for bracing and reinforcing the structure of 120 125 130

the barrel. The assembly of the barrel is simple, requiring only a suitable mounting block to support the lower section of the barrel designated by numeral 74. The disk 79 is then put in place within this section 74, by slipping the same in place between the brackets such as 77 and 78. It will be understood, of course, that there are oppositely located companion brackets for supporting the disk 79 against axial displacement within the barrel. The upper section 73 is then simply joined to the lower section 74, the brackets 76 and 75 and their oppositely located companion brackets holding the spacer disk 79 in place.

The recessed end closure is shown in a perspective view in Figure 3 and in a transversal cross section in Figure 4. It will be seen that this closure has a recessed portion 96 and a laterally extending flange 97. A central opening 98 is provided in this end closure, which, when the closure is attached to the tubular barrel shown in Figure 2, will register with the centrally located opening 146 provided in the spacer disk 79. Radially extending openings such as 99 are provided in the end closure which may be brought in register with the corresponding openings at the end of the tubular barrel members where the openings are designated by reference numerals 80 to 95, inclusive. It is, of course, understood that there are two such end closures provided, and that this closure, as shown in Figures 3 and 4, may correspond to the closure designated by numeral 4 shown in Figure 1, or to the closure at the other end of the barrel.

The structure of the lateral flanges such as 2 and 3 shown in Figure 1, is more particularly illustrated in the Figures 5 and 6 which I will now describe.

Each of the flanges, as noted previously, comprises a plurality of sections assembled to form a ring shaped structure. Each section of this structure is composed of a tray like frame member such as the one shown in Figure 5. This frame is, of course, of metal and comprises two oppositely located curved sections 100 and 107 joined by the side walls 102 and 103. Openings such as 104, 105 and 106 are provided in the side walls 102 and 103 for joining the various sections to form the ring shaped flange. Radially extending openings 108 and 109 are provided in the curved wall portion 107 for fastening the assembled flange to the tubular barrel member.

The reinforcing detail illustrated in Figure 6 serves a double purpose. It contributes to strengthening the structure of each section of the flange, and in addition provides a channel structure closing the openings 101 in the rim of the frame shown in Figure 5 interiorly in order to prevent damage to the cable or injury to workmen in case one of the

keys or studs attached to the lagging bars, which are slipped into the openings 101, should accidentally separate from a lagging bar. It will be caught in the channel shaped structure 110 and may be conveniently removed through one of the openings 101. The arms 111 and 112 of the structure shown in Figure 6 are provided with suitable holes 115, 116 and 117 which, when this part is inserted into the frame shown in Figure 5, will register with the holes 104, 105 and 106 in the side walls of the frame. The bracket extensions 113 and 114 are provided with openings 118 and 119 which will register with the corresponding openings 108-109 in the curved frame wall shown in Figure 5 and designated by numeral 107.

The channel shaped reinforcing structure shown in Figure 6 is inserted into the frame structure shown in Figure 5, with the various openings in register, which completes a section of the flange. Eight such sections, completely assembled, are now joined to form the ring shaped flange as illustrated in Figure 1. When the flange is completely assembled, it is attached to the assembled tubular barrel body shown in Figure 2, with the radially extending openings registering with the openings at the end of the barrel members, designated in Figure 2 by numerals 80 to 95, inclusive. The end closure illustrated in Figures 3 and 4 is then put in place, with the recessed portion 96 inserted into the barrel and with the openings 99 also in register with the holes 80 to 95, inclusive, in the barrel member. Suitable bolts are then radially inserted through the sixteen radial holes and fastened by suitable bolts and nuts, such as 55 to 64, inclusive, as indicated in Figure 1. The essential parts of the reel are now joined to form a unitary structure.

It may be remarked at this point, that the disk 79, shown in Figure 2, does not primarily serve the purpose of bracing and of reinforcing the tubular barrel member, but rather to simplify the assembly of the barrel member. It is, of course, understood that this spacer disk 79 may be made of sufficient strength to serve as a support for the barrel member if desired. Likewise, the channel shaped cross bars 7 and 8 shown in Figure 1 as inserted into the recessed portion of the end closure 4 may not be absolutely necessary for supporting the reel structure. Their use is optional.

In Figures 8 and 9, I have shown a cross section and a more diagrammatic end view of the completely assembled reel. The spacer disk 79 is shown in Figure 8 supported between the brackets 76-76', 75-75', 77-77' and 78-78'. These brackets are permanently attached to the respective sections of the tubular barrel designated in this figure by numerals 73 and 74. They hold the spacer disk 79 against displacement axially to the

tubular barrel. It will be seen from this figure that the flanges 2 and 3 are attached to the ends of the tubular barrel peripherally, while the end closures 96 and 96' are slipped 5 into place, the recessed portion of the end closures engaging the tubular barrel interiorly, and the lateral flanges 97 and 97' of the end closures 96 and 96', respectively, overlapping the ends of the tubular barrel and 10 also the inner circle of the assembled flanges 2 and 3. The attachment of the end closures and the flanges 2 and 3 to the ends of the tubular barrel is by means of the radially extending bolts such as indicated at 124, 126, 15 128 and 130, which are fastened by means of the nuts 125, 127, 129 and 131. It will, of course, be understood, that the bolts and nuts above mentioned, correspond to the fastening of the assembly as indicated in Figure 1 20 by different reference numerals, i. e., by reference numerals 55 to 64, inclusive.

Exteriorly, but disposed within the recessed portions of the end closure 96 are the reinforcing channel shaped cross bars 25 178—132. Within the recessed portion of closure 96' are similar cross bars, one being shown at 138. Other cross bars, such as 141—140 and 134—135 are disposed within the interior of the tubular barrel member and 30 attached to the end closure, respectively, by means of bolts and nuts such as 136, 137, 184 and 187, holding the cross supporting bar attached to the end closure 96 and also holding the bearing plate 133 to this end closure, 35 as particularly seen in the end view of the assembly shown in Figure 9.

The bearing plates 133 and 139 are suitably shaped plates each provided with a centrally located opening 148 and 144, respectively, 40 and with suitable mounting openings, such as 149 to 152, inclusive, for receiving the bolts 136—137, 184—187, as shown in Figure 9. The plate is particularly shown in Figure 7. The left hand side of the assembly shown in 45 Figure 8 is, of course, also provided with suitable cross supporting bars and with a bearing plate 139. There is now an axial opening defined by the openings 144, 145, 146, 147 and 148, in the two bearing plates 133 and 139, 50 in the recessed portions of the end closures 96 and 96' and in the spacer disk 79. The assembly can be supported rotatably on a shaft extending through these centrally extending openings.

55 As shown in Figure 9, the circular assembly of the ring shaped sectional flange, comprising the eight sections, such as designated by reference numerals 161 to 168, inclusive, is accomplished by fastening these sections 60 by means of bolts or rivets such as indicated by reference numerals 169 to 174, inclusive. The attachment of the completely assembled flange to the tubular barrel member is indicated in Figure 9 by means of bolts such as 65 124, 175 and 176.

The sectional rim channel on the flanges is shown in Figure 8 at 120', 121', 122' and 123'. The purpose of this channel, as has been remarked previously, is to prevent the loss of 70 a locking key or stud separated from a lagging bar, thereby preventing damage.

In Figure 10 is shown the locking key for attachment to a lagging bar. The key has preferably a rectangular head 155, a shank 153 and a threaded portion 154.

75 Figure 11 illustrates an embodiment of a lagging bar 158 provided with two locking keys 156 and 157. Lagging bars as the one shown in this figure, are attached peripherally to the flanges of the reel, by inserting the heads of the keys into the T-shaped openings provided on the periphery. The lagging bars are then slipped circularly in place on the flanges, with the shanks of the keys engaging the legs of the T-shaped openings and the heads locking in the flange sections. It will be understood that this method of fastening the lagging bars to the flanges provides for secure attachment of the lagging bars in place of the flanges which, as far as I am aware, is new in the art and presents 80 obvious advantages.

85 The lagging bar 159, shown in Figure 12, provided with a circular stud 160 is a blank for insertion at certain spaces around the circumference of the flanges as was explained 90 previously.

95 A steel tape may be wrapped peripherally around the lagging bars and attached to the blank or blanks for holding the lagging bars in place. The blank lagging bars, such as 100 the one shown in Figure 12, may be designated conspicuously by a certain color so that the attention of the workmen is called to removing the blank lagging bars first before 105 removing the keyed lagging bars. The steel tape may be provided with a seal guarding the reel against unauthorized opening.

110 In Figure 13 is shown the manner in which the lagging bars may be bundled for shipment, and which will be understood without elaborate description. Steel tape or wire 199 may be used for securing the lagging bars as shown, the ends of the wire or steel tape 199 being secured at 200.

115 The collapsed sections of the tubular barrel may be arranged for shipment as shown particularly in Figure 14. As shown in this figure, two sections of a collapsed barrel, 188 and 189, each having the spacer brackets 190—193, 194—196, respectively, are preferably shipped standing up and telescoped into each other as shown.

120 A modified arrangement of attaching the lagging bars is illustrated in Figure 15 which shows a fragmentary view of a reel comprising a barrel 203 and two lateral flanges 201 and 202. These flanges may be constructed in a similar manner as was discussed in connection with Figure 1, consisting of several 125 130

sections as indicated. The openings in the flanges are again T-shaped but extend axially instead of radially to the drum.

The lagging bars used in connection with

- 5 this modification are provided with keys such as 204 and 205, as is particularly shown in Figure 16. These laggings, marked in Figure 15 by numerals 206 and 207, are slipped in place endwise, with the keys or studs engag-
10 ing the T-shaped slots. The lagging bars are thus secured against displacement radially to the reel and in one direction also against movement axially to the reel. A ring, such as 208 may then be attached to one of
15 the flanges by means of suitable elongated openings 209 and 210, engaging bolts on this flange, and finally secured in place by suitable nuts such as 211 and 212.

The advantage of this arrangement is in
20 uniform structure of the lagging bars, since blanks are eliminated; in uniform structure of the flange sections, since no openings for blank lagging bars are needed; and, finally in simplified assembly and in elimination of
25 the steel tape for holding the lagging bars, which in the first described embodiment is required. A further advantage lies in the fact that the reel may be opened, i. e., the removal of the lagging bars may be started at any
30 point after removal of the collecting holding ring 208. A padlock or other seal may be provided for holding the ring in locked position against unauthorized removal.

This ring, as is shown in Figure 17, may
35 be made of sections, such as 213 to 220, inclusive, each provided with openings such as 221—222, 223—224, 225—226, etc., 235—236. These sections are preferably made of resilient material and successively slipped in
40 place, with the openings engaging suitable stationary headed studs on the flanges. The last section due to being resilient will bend and slip into place over the first section. All sections are now locked in place and securely
45 lock the lagging bars. When removal of the lagging bars is desired, any one of the resilient ring sections may be removed by simply prying its end over the end of the adjacent section and then moving the same circularly
50 out of engagement.

Such a locking ring as shown in Figure 15, which is secured by means of nuts or bolts provided either stationary or inserted loosely in the flange, may be found inconvenient
55 due to the necessity of first removing the nuts before the ring can be removed, although, it may be mentioned, this is appreciably simpler than other methods of securing the laggings. The arrangement can be further simplified,
60 however, by adopting the locking provision shown in Figure 18, which requires only headed bolts attached to the flange, and a ring having slots such as 237 for engaging these headed bolts. The ring is locked by a
65 latch 238 fastened on a bracket 239 and pro-

vided with a spring 240. The latch member is adapted to engage suitable steps in the ring and to lock the same with the headed bolts engaging the openings such as 237.

It is also contemplated to provide, in one modification, as shown in Figures 19 and 20, a sectional ring the sections of which may always remain on the flange. Each section of this ring is provided with angular slots such as 242 to 245, inclusive. With the lagging bars removed from the flanges, the sections are positioned as shown in Figure 19, attached to the flange by means of suitable bolts and nuts 246 to 249, inclusive.

When the lagging bars are attached and it is desired to lock them in place against displacement, each of the sections of the locking ring will be moved radially to overlap the ends of some of the laggings, and then laterally, so that the bolts in the flanges engage the other end of the angular slots as shown in Figure 20. The nuts 246—249 are then tightened on the bolts, securing the sections of the ring in position. Numerals 250 and 251 in Figure 20 indicate the flange and the laggings, respectively, with the locking ring sections in locking position.

It will be understood that a padlock may be provided in connection with any of the locking rings which I have shown, so that only an authorized agent can gain access to the cable on the reel.

It may be desirable in certain cases, to provide large curved plates of metal for covering the storage space on a cable in preference to using lagging bars. Such cover plate is illustrated in Figures 21 and 22, respectively. It may be attached to the flanges similarly to the attachment described in connection with the lagging bars, by means of suitable locking keys or studs such as 252 and 253 shown on the plate in these figures.

It will be apparent that the use of metal cover plates as shown in Figures 21 and 22, or the use of lagging bars as previously explained is optional. Either the one or the other may be used alternately if desired, for protecting a shipment of cable secured on my novel reel.

It will be seen from the foregoing that the collapsible assembled metal reel and the novel method of attaching the lagging bars, as described, represents a radical departure from current methods of cable reel construction and protection of the cable. It incorporates numerous advantages and novel structural and functional features which will be appreciated by the trade as an advance in the art of making such reels and of protecting cables.

It will also be readily understood that the invention may be modified in parts or as a whole and adapted to serve a variety of purposes other than explained but inherently residing in its teachings. Therefore, al-

though I have shown and described certain structural embodiments of the invention for purposes of illustration, it will be understood that I do not wish to be limited in applying 5 the invention precisely as shown, but that I intend to utilize and exploit the same in all variations and embodiments which fall within the scope of the following claims.

I claim as my invention:

- 10 1. A cable reel, having a tubular cable support comprising a plurality of longitudinal radially joined sections, closures, flanges, and means for removably mounting a closure and a flange at each end of said support, comprising bolts each passing through aligned openings in a section, a closure and a flange.
- 15 2. A cable reel, having a tubular support comprising a plurality of sections, a disk centrally disposed within said sections, means 20 permanently disposed within said sections for holding said disk against axial displacement, and laterally extending flange means peripherally attached at each end of said support for securing said sections in assembly.
- 25 3. A cable reel structure, having a plurality of radially assembled longitudinal sections forming a tubular central body, a disk disposed centrally within said body, means for securing said disk against axial displacement within said body, flange means removably attached at each end of said body for securing said sections against radial displacement and for defining the attachment of said reel, and centrally disposed openings in said 30 disk and in said flange means for receiving a bearing shaft for movably supporting said reel.
- 40 4. A reel for supporting cables, having a collapsible tubular central portion comprising a plurality of sections, recessed end plates, substantially ring shaped assembled flanges comprising a plurality of interchangeable sections, and means for removably joining an end plate and a flange to each 45 end of said central portion to form said reel and to hold the sections of said central portion in assembly.
- 50 5. A reel for supporting cables, having a collapsible tubular central portion comprising a plurality of sections, recessed end plates, substantially ring shaped assembled flanges comprising a plurality of interchangeable sections, means for removably and laterally joining an end plate and a flange 55 laterally to each end of said central portion to form said reel and to hold the sections of said central portion in assembly, a spacer disk disposed centrally within said central portion, and centrally disposed openings in 60 said disk and in said end plates for receiving a bearing shaft for rotatably mounting said reel.
- 65 6. A metal reel for supporting cables, having a collapsible tubular central body, end plates within the tubular body at the end

thereof, substantially ring shaped flanges on the outer side of the tubular body, means for removably attaching an end plate and a flange laterally to each end of said body to form said reel, axially disposed peripheral extensions on each of said flanges and integral therewith, openings circularly arranged in said peripheral extensions, a plurality of cross bars, and means on each of said cross bars for securing the same across said flanges by means of said openings.

7. A metal reel for supporting cables, having a plurality of central sections disposed to form a collapsible tubular central body, a spacer disk disposed centrally within said body, means for holding said disk against axial displacement within said body, a circularly recessed closure provided with a lateral flange disposed at each end of said body for closing the ends thereof, a ring shaped flange of substantially channel shaped cross section disposed peripherally at each end of said body, means for joining said flange and said recessed closure laterally with said body at each end thereof for holding said central sections in assembly, and central openings in said spacer disk and in said recessed closures for receiving a bearing shaft for rotatably mounting said reel when assembled.

8. A metal cable reel, having a plurality of central sections disposed to form a collapsible tubular central body, a spacer disk disposed centrally within said body, means for holding said disk against axial displacement within said body, a circularly recessed closure provided with a lateral flange disposed at each end of said body for closing the ends thereof, a ring shaped flange of substantially channel shaped cross section disposed peripherally at each end of said body, means for joining said flange and said recessed closure laterally with said body at each end thereof for holding said central sections in assembly, central openings in said spacer disk and in said recessed closures for receiving a bearing shaft for rotatably mounting said reel when assembled, a plurality of openings peripherally disposed on each of said ring shaped flanges, a plurality of cross bars for attachment to said flanges across the width defined by said central body, and locking means on each of said cross bars for engaging said peripheral openings on said flanges.

9. A metal cable reel, having a plurality of central sections disposed to form a collapsible tubular central body, a spacer disk disposed centrally within said body, means for holding said disk against axial displacement within said body, a circularly recessed closure provided with a lateral flange disposed at each end of said body for closing the ends thereof, a ring shaped flange of substantially channel shaped cross section disposed peripherally at each end of said body, said

- flanges comprising a plurality of interchangeable sections, a substantially channel shaped reinforcing member attached to each of said flange sections, means for joining said flange and said recessed closure laterally with said body at each end thereof for holding said central sections in assembly, central openings in said spacer disk and in said recessed closures for receiving a bearing shaft for rotatably mounting said reel when assembled, a plurality of openings peripherally disposed on each of said ring shaped flanges, and a plurality of cross bars for attachment to said openings in said flanges across the width defined by said central body. 10. In a cable reel, a tubular central body, a flange member disposed laterally at each end of said body defining the axial storage space of said reel, a circularly extending sectional channel provided peripherally on said flanges and having a plurality of peripheral openings, cross bars for peripheral attachment to said flanges to close said storage space, a plurality of locking keys attached to each of said cross bars for engaging said peripheral openings in said flanges and for locking said bars to said flanges, a closure attached at each end of said central body, and central openings in each of said closures for receiving a bearing shaft for rotatably supporting said reel. 11. In a cable reel, a collapsible tubular central metal body comprising a plurality of sections, laterally disposed metal flanges defining the axial storage space of said reel, metal end plates closing said body and having openings for rotatably supporting said reel, a plurality of cross bars for covering said storage space, cooperating means on said cross bars and on said flanges for detachably securing said cross bars, and means including bolts each extending through a hole in a flange, a hole in a section of the body portion and a hole in an end plate for securing said flanges and said end plates to said central body to secure said body against collapsing. 12. In a cable reel structure comprising a drum portion and end flanges defining the storage space of said reel, lagging bars for peripheral attachment to said flanges to close said storage space, means including T-shaped openings on said flanges for locking said laggings individually against displacement in one direction, and means for collectively locking said lagging bars against displacement in another direction. 13. In a cable reel structure comprising a drum portion and end flanges defining the storage space of said reel, cross bars for peripheral attachment to said flanges to close said storage space, cooperating means on said cross bars and on said flanges for locking said cross bars individually in place, and means on one of said flanges cooperating with said cross bars for locking said cross bars collectively in place on said flanges. 14. A reel including a sheet metal drum supported between a pair of head members at the opposite ends, each head member comprising an annulus having an outwardly extending flange along its inner periphery and fitting over the end of the drum, a separate ring within the drum at the end thereof, and bolts extending radially of the reel through the flange, the drum and the ring for securing the parts together. 15. A reel including a sheet metal drum supported between a pair of head members at the opposite ends, each head member comprising an annulus having an outwardly extending flange along its inner periphery and fitting over the end of the drum, a separate ring within the drum at the end thereof, and bolts extending radially of the reel through the flange, the drum and the ring for securing the parts together, the drum being imperforate along the portion of its cylindrical surface between the head members and comprising a plurality of separate sections in abutment with one another. In witness whereof, I hereunto subscribe my name this third day of June, 1930. LEO W. NACK.
